UNITED STATES PATENT OFFICE.

JOHN C. FIGG, OF BARRY, ILLINOIS.

BUGGY-BED.

SPECIFICATION forming part of Letters Patent No. 349,577, dated September 21, 1886.

Application filed June 2, 1886. Serial No. 203,890. (No model.)

To all whom it may concern:

Be it known that I, JOHN C. FIGG, a citizen of the United States of America, residing at Barry, in the county of Pike and State of Illinois, have invented certain new and useful Improvements in Buggy-Beds, of which the following is a specification, reference being had therein to the accompanying drawings.

This invention pertains to new and useful improvements in buggy-beds; and it consists, chiefly, in applying the seat and foot-rest directly to the side springs of the vehicle, and in the construction, combination, and arrangement of the parts, substantially as hereinafter fully set forth, and pointed out in the claims.

In the accompanying drawings, Figure 1 is a plan view of my invention, and Fig. 2 is a longitudinal sectional view thereof.

In carrying out my invention, I construct the wooden frame or body A of correspondingly-shaped side pieces, a a, the same being connected together at their front and rear ends by means of cross-bars a', each of the latter having a portion of its surface removed for securely connecting the side pieces and end bars together. This frame A is additionally connected together at its forward end by a second cross-bar, a'', which is likewise secured to the side pieces, and is at its center suitably braced with the front cross-bar, a', by means of a small connecting-bar, b.

Secured at or near each end of the frame A are four brackets, B, the straight or flat portion of which is provided with apertures for insertion of screws, by which the said brackets are secured to the upper surface of the frame A. Said brackets are curved outwardly a short distance and then rearwardly, at which point the ends of each are again bent into small eyes or hooks, b', formed by bending the ends of said bracket over against itself, the purpose of which eyes or hooks will be seen further on.

C C are two slightly-curved side springs, the highest point of the curvature of which being at the center thereof, and each end of the said springs is turned up or curved, forming a small hook for securing thereto one end of a square link or hanger, D, the other end of the said link being secured to the eye or hook b' of the bracket B, thus pivotally supporting or securing each end of the spring C. To the center of the side springs, C C, are secured the sides

of a seat, E, the same being rigidly secured to the said springs by means of screws or other ordinary means, the seat for this purpose being provided with small brackets or supports d, on its under side at or near each end thereof.

F is the foot-rest for the person or persons seated in the seat E, said foot-rest being composed of a rearwardly-inclined nearly vertical board, e, a horizontal board, e', and a front dash-board, e'', the said boards being suitably connected one to the other. These boards e e' are additionally secured or held together by means of flat braces, G, which braces are also secured to the under side of the seat E and to the rear and under side, respectively, of the rear and horizontal boards of the foot-rest. The foot-rest F is additionally braced by means of brace-rods f, connected to the under side of the seat E, and at or near the lower end of the board e, and the horizontal board e' is further secured or braced by means of brace-rods f', secured to the front of the rear board and to the upper surface of the horizontal board e', at or near the forward end thereof. From this it will be seen that the seat is attached directly to the side springs of the vehicle, and that the foot-rest, being secured directly to the said seat and independent of the frame of the buggy, the ready yielding of the springs and the accommodation of the seat and its foot-rest are provided for according to the weight of the person or persons occupying the seat. The links or hangers D are pivotally connected at both ends, thereby providing for the ready yielding of the ends of the springs as above stated.

I am aware that it is not new to provide a buggy with springs mounted on side bars, and a seat secured on the said spring-bars having a foot-board arranged between the side bars and connected to the ends of said springs by cranks or pivoted arms; also, a buggy having rigid spring-hangers and half-elliptical side springs pivoted to said hangers; but my invention is designed as an improvement over both of the inventions above designated; and to this end I secure directly to the vehicle-seat the foot-rest by means of braces and brace-rods, and secure said seat directly to the sidesprings, thus avoiding the obvious disadvantage in securing the foot-rest to the ends of the side springs, which latter in my invention are de-

signed only to receive the weight of the person occupying the vehicle-seat, and the weight is thus applied directly to the springs, so as to equally distribute the strain thereon.

5 Having thus described my invention, what I claim, and desire to secure by Letters Patent, is—

The seat secured to the side springs of a vehicle, the foot-rest secured to said seat, the 10 brace-rods connected to the rear board of said

foot-rest and the under side of the vehicle-seat and to the horizontal board, respectively, and the flat braces, substantially as shown and described.

In testimony whereof I affix my signature in 15 presence of two witnesses.

JOHN C. FIGG.
